SMOKER'S ARTICLE

Emanuel Joseph Sonn, Bridgeboro, N. J.

Application March 25, 1941, Serial No. 385,042

4 Claims. (Cl. 131—190)

My invention relates to smokers' articles, such as pipes and holders for cigars, cigarettes, cheroots and other tobacco products for the consuming or smoking thereof.

An object of my invention is the provision of regulable means for mixing relatively cool and smoke-strength-attenuating air in with the smoke in any proportion suited to the individual smoker's taste and need for a comfortable, cool smoke.

Another object is the provision of a facilely insertable and removable plug.

Another object is to reinforce the bit against excessive biting thereof by the smoker.

Another object is the provision of means for facilely receiving the end of a cigarette without mutilation particularly of the paper thereof.

Another object is the provision of a removable bit.

Other objects and advantages present themselves during the course of examining this specification and the accompanying drawing, in which—

Figure 1 is a perspective view of a cigarette holder embodying my invention, dotted lines indicating a cigarette retained thereby, as well as a part of the face of a smoker using said cigarette holder.

Figure 2 is a longitudinal sectional view of said holder.

Figure 3 is a cross-sectional view taken in the plane 3—3 therein.

Figure 4 is a cross-sectional view taken in the plane 4—4 therein.

Figure 5 is a cross-sectional view taken in the plane 5—5 therein.

Figure 6 is a perspective view of one of two mutually separable parts, also shown in Figures 1, 2 and 3, together constituting the mouth or seat retaining a cigarette at and by an end thereof.

Figure 7 is a perspective view of a removable bit, appearing also in Figures 1 and 2.

Figure 8 is a fragmentary, plan view of an alternative form of plug integral with a certain liner in said holder.

Figure 9 is a sectional view taken in the plane 9—9 therein.

Figure 10 is a perspective view of an alternative form of removable plug in association with a certain liner.

Figure 11 is a cross-sectional view taken in the plane 11—11 in Figure 2.

Referring to Figures 1 to 7 inclusive and 11, rotatable stem 12 is rotatably mounted on metal, tubular liner 13, in turn mounting the relatively

non-rotatable stem 14 and bit 15, the numeral 16 indicating a perforated plug integral with and extending from the tobacco-adjacent end of said liner, some of the perforations in said plug being indicated by the numerals 17.

The tobacco-adjacent end 18 of stem 12 is internally helically threaded to receive the two tapering, correspondingly helically threaded half-shanks 19 and 20 of the longitudinally split 10 mouth or seat, constituted of parts 21 and 22, the smoke-passage thereof being indicated by 23.

The numeral 24 indicates the smoker's head in part, the numeral 25 indicating the cigarette retained by and within said mouth or seat, the dotted lines 26 indicating the disposition thereof when partly screwed out, extended or expanded to receive the end of said cigarette.

Smoke-passage 23 communicates with perforations 17, the combined areas of the latter being not less than that of the former, preferably. Liner 13 is provided with air-inlet port 27. Rotatable stem 12 is provided with thereto correspondingly dimensioned air-inlet port 28, both of said ports being longitudinally correspondingly disposed, whereby the rotation of stem 12 around liner 13 can cause smoke-with-air passage 29 inside of liner 13 to communicate with the outside air externally of stem 12 to the fullest extent conditioned by the size of said air-inlet ports or to a lesser extent thereof, or to altogether prevent communication of passage 29 with said outside air.

The intermediate smoke-passage interiorly of plug 16 is indicated by 30. Cross-sectionally regarded, smoke-with-air passage 29 is substantially at least equal in size to the combined size of smoke-passage 23 and air-inlet 27—28.

Referring to Figures 8 and 9, the alternative form of plug is indicated by 31 and the smoke-passage thereof by 32, said plug being a therewith integral extension of liner 13.

In Figure 10, a novel form of partly flattened plug 33—34 provided with a therewithin disposed smoke-passage 35 is shown retained by and within the tobacco-adjacent end of metal, tubular liner 36, otherwise similar to liner 13. Obviously the flattened, tobacco-adjacent part 33 of plug 33—34 may be said to have an attenuated cross-sectional form, part 34 thereof being adapted to being securely gripped by twistingly removing plug 33—34 from or inserting it into liner 36. A removable plug is adapted to more thorough cleaning as well as to replacement of parts of the article.

As can be seen in Figure 2, liner 13 extends

through the entire length of bit 15 so as to become visible at the smoker-adjacent or mouth-adjacent end thereof to the naked eye. As can be seen in Figure 11, the liner assumes an oval or non-circular cross-sectional form at the bit, although I do not propose to have the scope of my invention limited to a non-circular form. The assembling of the bit and the liner may be effected by introducing the liner, plug-end first, into the mouth-adjacent end of the bit. The disposition of the metal liner at said end of the bit serves to considerably strengthen it thereat and considerably prolong the life thereof and make it resistant particularly against chewing thereof on the part of the smoker. It will be noted that my construction lends itself to particularly facile cleaning of the article in that the passages therein present a minimum of corners and sudden changes in direction.

Although I feel I have illustrated my invention typically, it is obvious that other modifications within the spirit and scope thereof can readily suggest themselves to persons skilled in the art without involving creative or inventive changes therein.

I claim:

1. A smoker's article comprising a tobacco-product-holding, longitudinally split mouth having two tapered, correspondingly helically threaded shank parts and corresponding tobacco-product-receiving parts, said shank parts being axially spaced from the tobacco-product-receiving parts of said split mouth, each of said shank parts being integral with one of said receiving parts, which collectively have a circular cross-sectional form.

2. A smoker's article comprising a stem and a tobacco-product-holding, longitudinally split mouth having two tapering, correspondingly helically threaded shank parts, the mouth-adjacent end of said stem being correspondingly internally threaded to receive said shank parts

5 and corresponding tobacco-product-receiving parts, said shank parts being axially spaced from the tobacco-product-receiving parts of said split mouth, each of said shank parts being integral with one of said receiving parts, which collectively have a circular cross-sectional form.

3. A smoker's article comprising a tobacco-product-holding, longitudinally split mouth having a plurality of tapered, correspondingly helically threaded shank parts and corresponding tobacco-product-receiving parts, said shank parts being axially spaced from the tobacco-product-receiving parts of said split mouth, each 15 of said shank parts being integral with one of said receiving parts, which collectively have a circular cross-sectional form.

4. A smoker's article comprising a stem and a tobacco-product-holding, longitudinally split mouth having a plurality of tapering, correspondingly helically threaded shank parts, the mouth-adjacent end of said stem being correspondingly internally threaded to receive said shank parts and corresponding tobacco-product-receiving parts, said shank parts being axially spaced from the tobacco-product-receiving parts of said split mouth, each of said shank parts being integral with one of said receiving parts, which collectively have a circular cross-sectional form.

EMANUEL JOSEPH SONN.
